UNITED STATES PATENT OFFICE.

NIELS BACH, OF NEENAH, WISCONSIN, ASSIGNOR TO GEORGE BANTA PRINTING CO., OF MENASHA, WISCONSIN, A CORPORATION OF WISCONSIN.

BOOK AND BINDING THEREFOR.

SPECIFICATION forming part of Letters Patent No. 722,418, dated March 10, 1903.

Application filed October 27, 1902. Serial No. 128,955. (No model.)

To all whom it may concern:

Be it known that I, NIELS BACH, a citizen of the United States, residing at the city of Neenah, in the county of Winnebago and State 5 of Wisconsin, have invented certain new and useful Improvements in Books and Bindings Therefor, of which the following is a specification.

My invention relates to improvements in 10 bookbinding, and has, among other objects, to provide a book composed either of signatures or of separate loose sheets securely bound together in a desirable form capable of standing considerable wear and rough usage and 15 so sewed that the parting of the binding thread or threads in one or several places will not cause the book to separate or pull apart so long as the majority of the stitches hold.

My invention is peculiarly designed to be 20 used on books which are subject to considerable wear and hard usage—such, for example, as large art-books, check-books, and books of circulating libraries—and also for resewing old books the leaves of which have 25 become loosened by reason of the breaking of the threads at present commonly used in binding or by the tearing of the holes in the paper or from other causes, though the invention is equally adapted to binding new 30 books.

The accompanying sheet of drawings, wherein in like letters and numbers denote like parts throughout the several figures, will illustrate my invention.

35 Figure 1 shows a single section or signature A in perspective, the bands or binding-cords 4 in position in the saw-cuts 5, the figure illustrating the preferred manner in which the binding-thread is sewed through 40 the first signature. Fig. 2 shows the first signature A and the second signature B in perspective, said signatures being spread apart to more clearly illustrate the manner in which these two are bound together. Fig. 45 3 shows in perspective the body of a book made up of any desired number of signatures A B C D, &c., and illustrates the way in which the book is sewed together.

When the leaves have been arranged in order and separated into signatures, the openings or holes 6 are punched or otherwise

made through the book at intervals along a line near the edge of the back at any desired distance apart, preferably about half an inch apart and about one-sixteenth of an inch 55 from the edge of the paper. The holes in each signature or section register with the holes in every other signature or section. Some of the advantages of my invention may be obtained by omitting to punch the openings at this stage and making them with the needle or by stabbing or piercing with a thread-carrying device. The saw-cuts 5 are made in the back, and the bands or binding-cords 4 are inserted in them. I prefer to use 60 three of these bands ordinarily, though it is obvious that a greater or less number may be used.

Referring to Fig. 1, it will be observed that the sewing-thread 7 is first tied in the last 70 hole of one of the ends of the first signature (A in Fig. 1) and then overcast from side to side over the back through each of the holes 6 of signature A in an ordinary whipstitch, sewing over the bands 4, the thread 7 being 75 drawn through the holes by a needle or other suitable means. After the first signature A has thus been whipstitched or overcast the free end of the thread 7 is drawn through that one of the holes 6 of the signature B 80 which is in line with the last hole 6 through which the thread has passed in the signature A. Thread 7 passing through it is returned through the above-mentioned hole in the signature A. In this manner the thread is drawn 85 twice through each of the holes 6. The thread 7 is passed from the end holes just described across the back of the signature and drawn through the second hole in the signature B, repassing through the second hole in the signature A, and so on until the last hole in the 90 opposite end of the signature B is reached, when the thread is passed and repassed through the holes 6 of the signatures B and C, uniting them in the same manner that the 95 signatures A and B were united. In like manner all of the signatures of the book are bound together, the end of the thread after being drawn through each of the holes 6 being secured to prevent its pulling loose by tying or 100 other suitable means. It will be observed that each hole 6 has had the thread 7 passed

and repassed through it, thus making a double strand. The backs of the signatures I prefer to glue in the usual way, preferably by applying with a brush suitable adhesive cement. It will be observed that the binding-threads are drawn across the backs of the signatures, so that when the back of the book is covered with glue or other suitable cement each stitch exposed is stuck fast to the back. 5 It will thus be seen that each stitch is separately secured through the book to the back and that this construction is firmer, stronger, and more durable than those now in use. A book constructed according to my invention 10 will not readily pull apart or break, while the pages will open as freely as in the ordinary whipstitched book. The relative distance between the holes 6 may be changed to avoid coinciding with old holes or cuts in books 15 which it is desired to rebind without materially weakening my construction.

While in the drawings I have shown only one thread 7, it is obvious that more than one thread may be used, and while I prefer to secure the thread at the end of the outermost 20 signature many of the advantages of my invention may be had by securing one end of each of two threads to the two middle holes of the outermost signature, overcasting each in 25 opposite direction to the other, and so on, carrying each thread through half the whole number of openings in each succeeding signature.

It will be seen that if the thread or threads 30 7 be drawn through more than one signature or if they be drawn through all the signatures at one stitch through carelessness on the part of the operator or for other reasons the construction of my book will still hold. So, also, by securing each stitch to the back if the 35 threads break in several places the book will not pull apart so long as a few stitches hold.

Having thus described my invention in its preferred form, what I claim, and desire to secure by Letters Patent of the United States, 40 is—

1. A book composed of signatures provided with registering holes lengthwise the back near the binding edge of each signature, the outermost signature and the adjacent signature 45 stitched together by a continuous thread or threads through holes in each, said adjacent signature and the succeeding signature being similarly united, and so on through the holes in each succeeding signature of the book, substantially as described.

2. A book composed of signatures provided with registering holes lengthwise the back near the binding edge of each signature, the outermost signature and the adjacent signature 50 stitched together by a thread drawn through the holes in each and across the binding edge, said adjacent signature and the succeeding signature being similarly united, and so on through the holes in each succeeding signature of the book, substantially as described.

3. A book composed of signatures or sec-

tions provided with registering holes lengthwise the back near the binding edge of each section, a thread stitched through each of the 70 holes of one of the outermost sections from side to side across the back of it and extending from the first to the last of the series of holes, said thread stitched in reverse direction through the nearest end hole of the adjacent section and again through the corresponding hole of the first-mentioned section, thence from side to side across the backs of the two sections and successively through 75 each of the holes in the adjacent section and each corresponding hole in the first-mentioned section in turn, and so on, fastening together in like manner in succession one after the other all the adjacent sections of 80 said book.

4. A book composed of signatures or sections provided with holes registering lengthwise the back near the binding edge of each section, a thread or threads stitched through each of the holes of one of the outermost sections from side to side across the back of it and extending from end to end of the series 90 of holes, said thread stitched in reverse directions through the nearest end hole of the adjacent section and again through the corresponding hole of the first-mentioned section, thence from side to side across the backs of the two sections and successively through 95 each of the holes in the adjacent section and each corresponding hole in the first-mentioned section in turn, and so on, fastening together 100 in like manner in succession, one after the other, all the adjacent sections of each book, the portion of said threads exposed on the binding edges being glued or otherwise cemented thereto.

5. A book having its sections or signatures provided with a set of holes at intervals along a line near the binding edge, the holes of one signature in alignment with the holes of every 110 other signature, a binding-thread drawn from side to side and over the back through each of the holes in the outside signature, beginning with the end hole and passing successively through the others, said thread being returned stitched through the end hole of the first-mentioned signature from side to side 115 and across the backs of both signatures, and so on in this order through each of the holes in each succeeding signature and the signature adjacent thereto, binding together 120 successively adjacent signatures throughout the book.

6. A book having a binding-thread stitched from side to side through the outermost section across the binding edge along a line near 125 said edge, said thread at the end of the line being stitched in return direction back through one or more adjacent sections, each stitch passed therethrough and back through the nearest opening made to admit the thread in the outermost section first served, said thread being stitched from side to side through 130 said sections across their binding edges along

a line near said edge in alinement with the opening in said outermost section, and so on through each of the succeeding sections, substantially as described.

- 5 7. A book composed of sections having a binding thread or threads stitched from side to side through the outermost section across the binding edge along a line near said edge, said thread at the end of the line being re-
10 turn-stitched through the adjacent section, each stitch passed therethrough and back through the nearest opening made to admit the threads in said outermost section, said threads being stitched from side to side
15 through both sections across their binding edges along a line near said edge in alinement with the openings in said outermost section,

and so on through each of the succeeding sections, the portion of said threads exposed on the binding edge being glued or otherwise cemented thereto, substantially as described. 20

8. A book composed of signatures having a set of registering holes at intervals lengthwise the back near the binding edge, saw-cuts made across said binding edges intermediate of any two of said holes, binding-cords adapted to fit in said cuts, said signatures being united by threads drawn across said binding edges over said binding-cords and through said holes, substantially as described. 25 30
